E. G. PETRIE,
SEARCH OR POCKET LIGHT SUPPORT.
APPLICATION FILED MAY 16, 1919.

1,362,177.

Patented Dec. 14, 1920.

Inventor:
Edward G. Petrie,
By his Attorneys
Fraenkel and Richards.

UNITED STATES PATENT OFFICE.

EDWARD G. PETRIE, OF IRVINGTON, NEW JERSEY.

SEARCH OR POCKET LIGHT SUPPORT.

1,362,177.

Specification of Letters Patent. Patented Dec. 14, 1920.

Application filed May 16, 1919. Serial No. 297,509.

To all whom it may concern:

Be it known that I, EDWARD G. PETRIE, a citizen of the United States, residing at Irvington, in the county of Essex and State 5 of New Jersey, have invented certain new and useful Improvements in Search or Pocket Light Supports; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification. 15

This invention relates to improvements in electric search or spot-lights of the character which are carried in the hand; and, the present invention has reference, more particularly, to provide the cylindrical barrels or casings of electric pocket search or spot lights, with a supporting means, when in use, whereby the search or spot light can be placed in an angular position upon the 20 ground, table or bench, to enable the use of both hands of the person using the device in the performance of his work.

The present invention, therefore, has for its principal object to provide in connection 30 with an electric pocket search or spot-light, means which may be variously adjusted for the angular support of the search or spot-light to enable the use of both hands, and also to prevent the rolling about of the device, due to the usual cylindrical shape of 35 the barrel or casing in which the electrical instrumentalities are contained.

The invention has for its further object to so construct and arrange the supporting 40 means with relation to the cylindrical barrel or casing of the search or spot-light, that the said supporting means can be forced into circular relation about the barrel or casing, when not in use, so as to afford no obstruction 45 when carrying the search or spot-light in the pocket, or when the same is packed in a box or case.

The device is especially adapted for the use of autoists at night by resting the search 50 or spot-light upon the ground, when removing and replacing tires upon the wheels of the vehicle, or when working about the various mechanisms of the vehicle.

Other objects of the present invention not 55 at this time more particularly enumerated will be clearly understood from the follow-

ing detailed description of the present invention.

With the various objects of the present invention in view, the said invention consists 60 in the provision of an electric pocket search or spot-light with a novel and simply constructed supporting means for angularly placing the search or spot-light upon the ground, table, bench, or the like, to throw 65 the light directly upon the spot where required, and still permitting the operator to use both hands; and, the invention consists, furthermore, in the novel arrangements and combinations of the several devices and 70 parts, as well as in the details of the construction of the said parts, all of which will be more fully described in the following specification, and then finally embodied in the clauses of the claims which are appended 75 to and which form an essential part of the said specification.

The invention is clearly illustrated in the accompanying drawings in which:—

Figure 1 is a view of a fragmentary portion 80 of an electric pocket search or spot-light provided with a supporting means made according to the principles of the present invention, said supporting means being shown closed about the cylindrical barrel or 85 casing of the search or spot-light when the latter is not in its angularly supported position; and Fig. 2 is a cross-sectional representation of the same, said section being taken on line 2—2 in said Fig. 1. 90

Fig. 3 is a side elevation of the electric search or spot light and the supporting means in one of its operated positions, illustrating the manner of angularly supporting the search or spot-light upon a surface; and 95 Fig. 4 is a transverse vertical section of the same, said section being taken on line 4—4 in said Fig. 3.

Similar characters of reference are employed in all of said above described views, 100 to indicate corresponding parts.

Referring now to the said drawings, the reference-character 1 indicates the usual style of electric pocket search or spot-light, the same comprising the usual cylindrical 105 barrel or casing 2 provided at one end with the lens 3 and at its other end with the screw-cap 4. The reference-character 5 indicates the usual switch-device for establishing within said barrel or casing an electric circuit between the battery 6 and the electric lamp, the latter not being shown, 110

and both of which devices are of the usual and well-known constructions.

The herein-above mentioned supporting means consists, essentially of a cylindrical drum or shell, as 7, which is suitably mounted in a fixed position upon said barrel or casing 2, near the illuminating end-portion of the search or spot-light, the said drum or shell 7 being made in such a manner that a 10 circular space or chamber is provided between the said barrel or casing 2 and the concentrically disposed drum or shell 7. The latter is also provided with a pair of elongated guide-openings or slots 8 and 9, 15 and a pair of narrow openings or slots 10 and 11, the opening 10 being in alinement with the guide-opening or slot 8, and the opening 11 being in alinement with the guide-opening or slot 9, substantially as 20 shown in the several figures of the drawings.

Movably disposed within the above-mentioned circular space or chamber are a pair of supporting elements or members 12 and 13, said members or elements having their 25 respective ends 14 and 15, under normal initial conditions, projecting from the respective narrow openings or slots 10 and 11, and the respective members or elements 12 and 13 being provided at the other end-ports 30 with guiding studs or projections 16 and 17, or other suitable means, which respectively extend into and from the respective guide- openings or slots 8 and 9. To properly retain the said supporting members or elements 12 and 13 in their relative positions 35 within the cylindrical drum or shell 7, against inoperative displacement and to properly manipulate the said supporting members or elements 12 and 13, so as to 40 bring them from their encircling closed relation, shown in Figs. 1 and 2, to their supporting relation represented in Figs. 3 and 4, the said guiding studs or projections 16 and 17 are respectively provided upon their 45 projecting end-ports with manipulating means, such as heads or buttons 18 and 19, or other suitable devices, which as is illustrated more particularly in Figs. 1 and 3 are of greater width than the width of the 50 openings or slots 8 and 9, so as to project laterally across said slots, as will be clearly understood from an inspection of the several figures of the drawings. That the said supporting members or elements 12 and 13 55 will readily wind themselves about the cylindrical barrel or casing 2, within the drum or shell 7, or that they will straighten out into their supporting relation, when manipulated, each supporting member or element 60 is made of a metal having great resiliency, the preferred metal to be used being pieces of flat spring-steel, as here shown. Having in the foregoing description set forth one general construction of supporting means for electric pocket-search or spot- 65

lights, I will now briefly set forth the manipulation of the supporting members or elements for angularly arranging the search or spot-light upon a surface in the manner illustrated in Figs. 3 and 4 of the drawings. 70

When the said supporting members or elements are thus to be arranged all that is necessary is to move the finger-pieces, heads or bottoms 18 and 19 in opposite directions, in the respective guide-openings or slots 8 75 and 9, whereby the respective members or elements 12 and 13 will be pushed from the respective openings or slots 10 and 11, the said members or elements, owing to the resiliency of the metal assuming the straightened-out and spread positions, indicated in said Fig. 4 of the drawings. When the said members or elements 12 and 13 are moved out to their fullest extent, the angular disposition of the search or spot-light is thirty 80 degrees or thereabout to the plane of the surface upon which it is placed; but, it will be evident that this angular arrangement may be varied, according to the degree of movement of the fingerpieces, whereby the 85 said supporting members or elements 12 and 13 may be variously extended in their straightened out relations from the openings 10 and 11, as will be clearly evident, the frictional contact of the wrapped portions of the said members or elements 12 and 13 within the drum 7 being such that the said members or elements 12 and 13 will be held in their adjusted positions, unless moved in either direction by means of 90 their manipulating means or fingerpieces 18 and 19.

I am fully aware, that changes may be made in the general arrangements and combinations of the various devices and parts, 105 as well as in the details of the construction of the said parts, without departing from the scope of the present invention as set forth in the foregoing specification and as defined in the clauses of the claim which are 110 appended thereto. Hence, I do not limit my present invention to the exact arrangements and combinations of the various devices and parts.

I claim:—

1. In an electric pocket search or spot-light, in combination with the inclosing barrel or casing thereof, a drum mounted upon and encircling said barrel or casing, and means disposed within said drum and normally encircling said barrel or casing, said means being adapted to be projected from said drum in straight relation for angularly supporting said search or spot-light upon a surface. 115

2. In an electric pocket search or spot-light, in combination with the inclosing barrel or casing thereof, a drum mounted upon and encircling said barrel or casing, and means movably and adjustably disposed 120

within said drum and normally encircling said barrel or casing, said means being adapted to be variously projected from said drum in straight relation for supporting said 5 search or spot-light at different angles upon a surface.

3. In an electric pocket search or spot-light, in combination with the inclosing barrel or casing thereof, a drum mounted upon 10 said barrel or casing, said drum being constructed so as to form with the barrel or casing an annular chamber, the shell of said drum being provided with a pair of elongated openings and a pair of small openings, 15 each small opening being in alignment with an elongated opening, a pair of resilient bands movably disposed in said chamber, each band having an end-portion projecting from a small opening, and means upon each 20 band extending into and from an elongated opening for manipulating said bands.

4. In an electric pocket search or spot-light, in combination with the inclosing barrel or casing thereof, a drum mounted upon 25 said barrel or casing, said drum being con-

structed so as to form with the barrel or casing an annular chamber, the shell of said drum being provided with a pair of elongated openings and a pair of small openings, 30 each small opening being in alignment with an elongated opening, a pair of resilient bands movably disposed in said chamber, each band having an end-portion projecting from a small opening, a guiding stud upon 35 each band, each stud extending into and from an elongated opening, and a finger-piece upon the extending portion of each stud for manipulation of said bands, each fingerpiece being of greater width and the width of the corresponding elongated opening 40 above which the fingerpiece is movably disposed.

In testimony, that I claim the invention set forth above I have hereunto set my hand this 14th day of May, 1919.

EDWARD G. PETRIE.
